UNITED STATES PATENT OFFICE.

CHARLES S. SHARP, OF AUBURN, NEW YORK, ASSIGNOR TO D. M. OSBORNE & COMPANY, OF AUBURN, NEW YORK, A CORPORATION OF NEW YORK.

MOWING-MACHINE.

SPECIFICATION forming part of Letters Patent No. 760,707, dated May 24, 1904.

Application filed May 27, 1901. Serial No. 61,979. (No model.)

To all whom it may concern:

Be it known that I, CHARLES S. SHARP, of Auburn, in the county of Cayuga and State of New York, have invented a certain new and 5 useful Mowing-Machine, of which the following is a specification.

My invention has for its object the production of particularly simple, economical, and efficient connections between the finger-bar 10 and coupling-frame of a mower; and it consists in the combination, construction, and arrangement of the component parts of the contiguous portions of said finger-bar and frame and the connections between the same, as hereinafter fully described, and pointed out in the 15 claim.

In describing this invention reference is had to the accompanying drawings, forming part of this specification, in which like letters indicate 20 corresponding parts in all the views.

Figure 1 is a top plan of a mowing-machine embodying my invention, a portion of the pole being broken away. Fig. 2 is an enlarged top plan of contiguous portions of 25 the finger-bar and the coupling-frame operatively connected together. Fig. 3 is a vertical sectional view taken on line 3 3, Fig. 1. Fig. 4 is a horizontal sectional view of the front connection between the finger-bar and 30 the coupling-frame. Fig. 5 is a rear elevation of the detached inner shoe for the finger-bar and the adjusting member journaled in said shoe. Fig. 6 is a horizontal sectional view taken on line 6 6, Fig. 5. Fig. 7 is an 35 enlarged plan view, partly in section, of a portion of the parts seen in Fig. 2.

A and B represent, respectively, the finger-bar and the coupling-frame of my mowing-machine, both of which parts may be of any 40 suitable form, size, and construction. Said finger-bar A and coupling-frame B are provided, respectively, with an inner shoe a and a yoke b, which, so far as this invention is concerned, form, essentially, parts of the finger-bar and the 45 coupling-frame. The yoke b is provided with a socket b', extending from the rear forwardly and having substantially vertical side walls b² b², as best shown in Figs. 2 and 3, and a

diagonal push-bar b³, forming part of the coupling-frame B, has a forward extension b⁴ 50 projecting into the socket. The extension of the push-bar is provided with an eye, through which the end of the frame-bar b⁵ extends. The yoke b is journaled upon the bar b⁵, and the extension b⁴ of the bar b³ cooperates with 55 the vertical walls b² on its opposite sides and limits the endwise movement of the yoke on the frame-bar b⁵.

The finger-bar A, or, more strictly speaking, its inner shoe a, is provided with separated 60 relatively fixed attaching parts or ears a' a², which rise upwardly from the contiguous portions of said finger-bar, are arranged one in advance of the other, and are connected independently to the coupling-frame B, and preferably to attaching parts or ears b' b⁷, depending from the yoke b, and also arranged one in advance of the other.

The parts or ears a' b⁶ are connected by a substantially horizontal pivot c, Fig. 4, which 70 has a limited play in a slot in the ear b⁶, and the contiguous surfaces of said parts or ears a' b⁶ are formed concavo-convex, so that the surface of the part or ear a' adjacent to the part or ear b⁶ is free to move relatively to said 75 part or ear b⁶ as the outer end of the finger-bar is forced forwardly or backwardly.

The parts or ears a² b⁷ are connected by an adjusting member c' and a substantially horizontal pivot c², Figs. 6 and 7, the adjusting 80 member c' being journaled in the part or ear a² and provided with an eccentrically-arranged opening and the pivot c² being passed through the part or ear b⁷ and through the eccentrically-arranged opening in the adjusting member c' and alined with the pivot c transversely to the length of the finger-bar A. Said adjusting member c' may be held in position by any suitable means, as a bolt c³, engaged with the part or ear a², and is thus prevented from 90 movement independently of said attaching part or ear a².

In the use of my mowing-machine whenever it is desired to force the outer end of the finger-bar forwardly or backwardly the bolt 95 c³ is loosened and the adjusting member c' is

partly rotated in the attaching part or ear a^2 , thus moving said part or ear laterally relatively to the other part or ear a' without varying the alinement of the pivots $c c'$. During 5 the adjustment of the finger-bar by the member c' the part or ear a' is free to move relatively to the part or ear b^6 to a limited extent for permitting the desired movement of the part or ear a^2 . After the desired adjustment 10 of the outer end of the finger-bar the bolt c^3 is tightened, whereupon said finger-bar is held in its adjusted position. When adjusting the finger-bar, it is usually unnecessary to adjust the bolt c ; but it will be understood that said 15 bolt may be adjusted, if desired.

The construction and operation of my mowing-machine will now be readily understood upon reference to the foregoing description and the accompanying drawings, and it will 20 be particularly noted that more or less change may be made in the component parts thereof without departing from the spirit of my invention.

Having thus fully described my invention, what I claim as new, and desire to secure by 25 Letters Patent, is—

In a mowing-machine, the combination of a coupling-frame bar, a yoke mounted on the coupling-frame bar and provided with a socket extending forwardly from a rear face thereof, and a diagonal push-bar formed with a forward extension projecting into the socket and connected to the coupling-frame bar, said extension coöperating with the side walls of the socket to limit the endwise movement of 30 the yoke on the coupling-frame bar, substantially as and for the purpose described.

In testimony whereof I have hereunto signed my name, in the presence of two attesting witnesses, at Auburn, in the county of Cayuga, 40 in the State of New York, this 10th day of May, 1901.

CHARLES S. SHARP.
